COMBINED CRUET SET AND TRAY THEREFOR

Augusto Salviato, Corso Mario Abbiate, 110,
Vercelli, Italy

Filed June 11, 1973, Ser. No. 368,892

Term of patent 14 years

Int. Cl. D7—06

U.S. Cl. D7—58

FIG. 1

FIG. 2

FIG. 4

FIG. 1 is a side perspective view of a combined cruet set and tray therefor showing my new design;

FIG. 2 is a top plan view thereof;

FIG. 3 is an end elevational view thereof; and

FIG. 4 is a bottom plan view thereof.

I claim:

The ornamental design for a combined cruet set and tray therefor, as shown.
